UNITED STATES PATENT OFFICE.

LAWSON B. STONE, OF MARBLEHEAD, MASSACHUSETTS.

AUTOMATIC SPRINKLER.

SPECIFICATION forming part of Letters Patent No. 349,764, dated September 28, 1886.

Application filed June 7, 1886. Serial No. 204,360. (No model.)

To all whom it may concern:

Be it known that I, LAWSON B. STONE, a citizen of the United States, residing at Marblehead, in the county of Essex and State of Massachusetts, have invented certain new and useful Improvements in Automatic Sprinklers; and I do hereby declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 This invention relates to "automatic thermostatic sprinklers" for fire or other purposes, the essential features of which consist, in connection with a suitable liquid-supply pipe and valve leading therefrom, of a hollow closed vessel adapted to contain some volatile fluid or gas. The latter, by expansion due to the influence of heat, causes a temporary relative displacement in the position of one side of said vessel to which the valve-stem is attached, and 20 thereby actuates the valve at certain times, as desired.

25 In my present invention I have endeavored to render my sprinkler entirely automatic, in contradistinction to such as have been operated by thermostatic influences, which cause the separation of certain parts, thus rendering the apparatus useless until again reset for a repetition of the operation.

One of the primary features consists in the 30 employment with the expansive closed vessel, to be filled with some volatile gas or fluid, of a supply-valve and valve-stem, which latter is attached to and is moved simultaneously with the active or flexible side of said vessel; hence 35 it will be perceived that the valve is operated and opened by the expansive pressure occasioned by thermometric changes, while it is normally kept closed by vacuum-pressure consequent upon removal of such cause—that is, 40 undue excess in the temperature surrounding it. Thus the sprinkler is perfectly automatic.

A second feature is embodied in means for 45 adjusting the expansive vessel to be actively operated at different degrees of temperature, according to the circumstances or locality in 50 which it is to be placed. This is effected by

the agency of a thumb-screw, whereby the rigid or unyielding side of the expansive vessel is varied in its distance from the yielding or active side, which is limited in one direction of movement by the contact of the valve upon its seat.

55 Thirdly, in the disposition of two deflector-plates forming a distributor, one of which is affixed upon and moves with the valve-rod, and 60 the other is adjustably secured to a fixed part of the apparatus. Thus the discharge-orifice of the sprinkler may be made greater or less to suit the varying circumstances—as head or 65 quantity of liquid—and thereby govern its distribution, while the direction and form of the liquid as it is ejected can be adjusted, respectively, by the difference in the size of the two and by their shape and flexibility, since they may 70 be corrugated or bent to disperse and vary the course of the liquid as it leaves the apparatus.

75 The drawings accompanying this specification represent in Figure 1 a vertical central section of a sprinkler embodying my invention in a closed or inactive position, while Fig. 2 is a similar section in an open position. Fig. 3 is a plan and Fig. 4 a detail view of a portion of the supporting-frame. Fig. 5 is a modified form of the flexible deflector-plate.

80 In said drawings, A represents a supply-pipe leading from any suitable reservoir from which a continuous supply of liquid under pressure can be obtained. This pipe may be arranged within a room and provided with a series of sprinklers, after the manner now 85 most generally approved. This sprinkler consists, primarily, in a circular casting or frame, B, composed of two sets of arms, *a a b b*, radially disposed one above the other and united by vertical pieces *c c*. This frame contains the operative parts of the apparatus, and 90 is removably joined and secured to the supply-pipe by a nipple or screw-threaded pipe, C. The lower end of this pipe forms a seat for the valve D, to which is attached the valve-stem 95 *d*. The latter extends through the bore of the nipple C, projects beyond a short distance, and is united and operates with the yielding side of an expansive vessel, E. This vessel is the active agent, through changes in the temperature surrounding it, by means of which the supply-valve is rendered active and open, or 100

inactive and closed, dependent upon circumstances, and is composed, preferably, of two circular disks, *e f*, bent and united to form a hollow closed vessel, which when completed is 5 to contain some volatile fluid or gas. In the present instance this vessel is secured within the frame *B* and attached to the arms *a a* by its upper disk, *e*, only, which latter is made rigid and unyielding. The instrumentality 10 by which it is adjustably secured to the frame consists in a screw-threaded stud, *s*, centrally located and forming part of said disk *e*. This stud is rectangular at its base and engages in a similarly-shaped hole in the arms *a a*, moving therein as it is operated by the thumb-nut *F*. The lower yielding flexible disk or diaphragm, *f*, is centrally united to the upper end of the valve-stem *d*, as shown. This disk is constructed so as to have resilient action 15 upon either side of a plane (see line 11) passing through its juncture with the fixed disk *e*; hence a pop action is insured and the valve is thrown its full extent of movement at one impulse. Such impulses are due either to expansion of the fluid within the vessel *E*, arising 20 from the application of heat, or from vacuum-pressure induced by the cessation of such disturbing cause.

To efficiently disperse and spray the liquid 25 emerging from the nipple *C* when the valve is open, I have arranged a compound distributor, *G*, which is composed of a deflector-plate, *h*, and a reflector-plate, *i*, both of which are preferably circular in form and located 30 within the frame *B* below the expansive vessel *E*. These operating parts form a very important part of my apparatus, since the efficiency of the latter is materially affected 35 by the manner in which the liquid is thrown 40 and dispersed. Therefore I have affixed the upper or deflector plate, *h*, firmly upon the valve-stem directly beneath the juncture of the latter with the yielding disk *f*. Furthermore, said plate is somewhat larger in diameter 45 than the expansive vessel *E*, but smaller than the reflector-plate *i*, with which it co-operates. The latter is adjustably secured upon the nipple *C*. Thus when actively employed 50 the flow of liquid can be regulated by the adjustment of the lower plate, *i*, so the sprinkler may be set to discharge a large or small amount, dependent upon the head of liquid or 55 the quantity required for the locality. Furthermore, the shape of the spray can be changed by flexible edges and by modifying the contour of the disks, as by radial corrugations; or, as is shown in Fig. 5 of the drawings, radial slits or cuts extending a short distance into the body of the plate may be made, and since 60 the metal composing them is to be very thin and flexible rapid vibrations are imparted to the lips *t t* by the passage of the escaping fluid, and the latter is more efficiently dispersed. The aperture in the arms *a a* is rectangular in 65 shape, as shown at *j* in Fig. 4, in order to prevent rotation of the valve and valve-stem.

Furthermore, to secure a tight joint, I have the valve-face *k* and its seat made from metals of different densities. Thus the contact of identically the same surfaces at each impact 70 secures the valve from leaking.

It is evident that the closed position of the valve is always predetermined, also that of the flexible disk *f* for a fixed length of valve-stem; hence the upper stiff disk, *e*, may be regulated 75 in position by the movement of the thumb-screw *F*, and by causing the disks *e f* to approach and contract the chamber in the vessel *E* the latter will act more readily or at a lower temperature. Reverse adjustment 80 would consequently cause opposite effects; hence the vessel would act less readily and a higher temperature be attained before activity 85 of the sprinkler could be secured. The rigidity of the upper disk, *e*, increases the durability of the expansion-chamber, as the adjusting devices of course do not bend it, as they would a flexible disk, and a certain amount of strain is thus avoided. All parts 90 of it are moved evenly together.

The operation of this apparatus is as follows, presuming the parts are in their normal positions, with the valve closed, as shown in Fig. 1: With a sufficient increase in the temperature above the normal the volatile fluid 95 or gas in the expansive vessel *E* is now expanded, with the result to actuate the yielding disk *f*. The latter, by a sudden resilient or pop action, moves to the position shown in Fig. 2, and carries with it the valve *D*, valve-stem *d*, 100 and the deflector-disk *h*, mounted thereon. The latter, from its proximity to the adjustable reflector-disk *i*, is now in the required position to most effectively disperse the liquid emerging 105 from the supply-pipe *A* by way of the nipple *C*. This activity of the sprinkler now continues so long as the thermostatic influences are such as to maintain the vessel *E* in an expanded state. When such cause ceases, 110 the vacuum produced within said vessel operates upon the yielding disk *f*, and the latter retroacts with respect to the disk *e*, thereby closing the valve tightly. As will be seen, the valve having opened, the water passes into the chamber formed by the reciprocating 115 disk *h*, fixed to the valve-stem, and the disk *i*, adjustable upon the nozzle of the nipple *C* toward the former and co-operating disk. Their flexible edges, approximating when actively disposed, compress the liquid, which escapes 120 in a thin sheet, which may be modified as required, to spread it in the space around.

There are several advantages attained in this sprinkler, prominent among which is this: The valve is always maintained closed 125 by the agency of the expansive vessel when the latter is inactive; hence the liquid may be withdrawn from the supply-pipe, and upon re-filling of the latter no danger ensues of flooding the apartment in which said sprinkler or 130 sprinklers are located. Thus it will be seen that the apparatus is entirely automatic and

adjustable to varying degrees of temperature, which may or may not produce activity, such or any predetermined degree being regulated by the distance between the disks *e f*, not by varying the quality of the volatile liquid contained between them.

I am aware that sprinklers have been made in which an expansive vessel induced by thermal variations in the temperature has been employed to both open and close a valve, which is adapted to control a fluid-supply. This device I do not desire to claim, broadly; but

What I consider as my invention, and wish to secure by Letters Patent, is—

1. In an automatic sprinkler, the supply-valve, its valve-rod, and the two co-operating deflector-plates, in combination with an expansive vessel, one side of which is attached to said valve-rod, for the purpose set forth.

2. The combination, with a supply-valve, its valve-stem, and the two oppositely-disposed deflector-plates, of the expansive fluid-

vessel and an adjusting screw and nut acting on one side of said vessel, substantially as and for the purpose set forth.

3. The combination, with the supply-pipe *A*, frame *B*, expansive vessel *E*, secured thereto, nipple *C*, and reflector-plate *i*, of the valve *D* and valve-stem *d*, carrying the deflector-plate *h*, all united and actuated by said vessel *E*, substantially as herein stated.

4. In combination with the pipe *C*, through which the fire-extinguishing fluid passes, the flexible distributing-plates *h i*, arranged edge to edge at the mouth of said tube, one of said plates being adjustable on the latter to vary the distance between them, substantially as set forth.

In testimony whereof I affix my signature in presence of two witnesses.

LAWSON B. STONE.
